CAGE-MAKING MACHINE

Application filed August 29, 1927. Serial No. 216,090.

Our invention relates to the art of reinforcing concrete and it has particular relation to machines suitable for making reinforcing cages for concrete poles.

Such reinforcing cages comprise a plurality of longitudinal rods on which iron wire is spirally wound. The winding operation is usually accomplished in a lathe provided with suitable means for holding the rods. The 10 spirally wound wire and the rods are wired together at their junctions to provide a rigid structure.

Heretofore, in winding the spiral wrapping wire, the rods were supported on a mandrel 15 which was provided with suitably spaced, rigidly fastened discs for engaging the rods. After the spirally wound wrapping is completed, however, the rods are tightly engaged on the discs and removal of the finished cage 20 is difficult.

It is, therefore, an object of our invention to provide a machine for expediting the manufacture of such reinforcing cages.

Another object of our invention is to provide 25 a machine such that the finished cage may be easily withdrawn from the mandrel.

Still other objects of our invention will become apparent from the following description of the structure and operation of our 30 device.

In the accompanying drawing, Figure 1 is an elevational view of our reinforcing cage making machine, a portion of the structure being shown as broken away in order to illustrate the component parts in greater detail;

Fig. 2 is a cross-sectional view of the face-plate assembly of our cage-making machine;

Fig. 3 is a view, partially in cross-section and partially in elevation, of one of the supports for holding the reinforcing rods in place on the mandrel of the cage-making machine, and

Fig. 4 is an end view, partially in elevation and partially in section, of the support shown 45 in Fig. 3.

Referring to Fig. 1, our cage-making machine comprises a lathe bed 1 upon which are mounted the usual driving motor 2 and head stock 3. The tail stock 4 is of different construction from the tail stock known to the art and its construction and operation will be hereinafter described.

The mandrel 5 upon which the cage is wound is supported by two stub shafts 6 and 7, which are respectively carried by the head 55 stock 3 and the tail stock 4.

The mandrel 5 comprises two sections of pipe, a large-diameter pipe 8 and a small-diameter pipe 9, the relative sizes being such that the small pipe makes a snug fit with the large one. The pipes may be moved with relation to one another by heating the large pipe and thus expanding it to permit relative motion of one pipe within the other. Such telescoping of the two pipes permits lengthening or shortening the mandrel to accommodate different length cages. The mandrel is driven through suitable reduction gearing 12 from the motor 2, which is controlled by means of a switch arm 13 to which is attached 60 a pull rope 14, so that the motor may be controlled from any position along the length of the lathe bed.

The face plate 15 (see also Fig. 2) for supporting the reinforcing rods 16 comprises two 75 members, a fixed plate 17 rigidly attached to the mandrel shaft and provided with slots 21 about its peripheral edge, and a longitudinally slidably plate 22 provided with stripper pins 23 adapted to engage suitable openings 80 24 in the fixed plate, so that when the movable plate is forced to the right the reinforcing rods 16 are driven longitudinally out of engagement with the slots in the fixed plate.

The fixed face plate 17 is provided with a 85 collar 25 fastened about the mandrel and having a flange 26 at its left end. The movable face plate 22 is mounted upon this collar, a loose collar 27 being mounted between the movable face plate and the flange of the first 90

named collar and being prevented from rotating by means of a strap 31 which engages the lathe bed. A forked lever arm 32 is pivotally mounted on the slidable collar 27 and is provided with cam surfaces 33 (Fig. 2) such that when the lever arm is forced to the right the cam surfaces cause the slidable face plate 22 to drive the reinforcing rods 16 out of engagement with the fixed face plate 17.

- 10 A spring 34 is preferably disposed between the fixed and the slidable face plates in order to prevent accidental engagement of the stripper pins with the reinforcing rods and to withdraw the stripper pins from the openings 15 24 after the finished cage has been disengaged from the mandrel.

A number of supports 35, such as shown in detail in Fig. 3, are provided at suitable intervals along the mandrel. These supports comprise a disc 37 fastened to the mandrel. Clevis members 38 are fastened to this disc and provide a pivotal support 36 for a plurality of dogs 40. The ends of the dogs are provided with a notched V-shaped surface so that 20 the reinforcing cage rods may be supported therein. The high-points 39 of the end surfaces of the dogs lie close to the face of the disc, so that when the dog is against the disc, the radially inward pressure of the rod will 25 tend to keep the dog in the engaged position. To further aid in keeping the dogs in engaged position, a slidable disc 41 is provided with a flange 42 which engages the exposed face of the dogs and holds them against the face of 30 the disc 37. A collar 43 is also held on the mandrel by means of screw 44, and a spring 45, disposed between the slidable collar 41 and the stationary collar 44, is adapted to drive the slidable disc against the dogs.

- 40 When the reinforcing rods are first placed on the mandrel, it is necessary to hold them on the several discs and this is done by means of the structure shown in Fig. 3 and Fig. 4. Holding members 47, pivoted about bolts 48 45 in discs 37, are provided with hook-shaped ends 49 to engage the rods 16. Springs 51 are fastened between intermediate portions 52 of the hooks and are so disposed that when the hooks are engaged on the rods, the spring forms, with the hooks, a toggle structure which is adapted to hold the hooks in engaged position.

The tail stock 4 (Fig. 1) is mounted on a 50 heavy rod 55 which is fastened to the lathe bed. The rod is located back to the center line of the lathe and the tail stock may be swung up and back out of engagement with the mandrel. When the tail stock is in operative position, it is held down by a latch mechanism 56.

The tail stock stub shaft 7 is provided with a disc 53 at its inner end for supporting the ends of the reinforcing rods. Openings 54 are provided in the periphery of the disc and, consequently, the reinforcing cage may be ro-

tated by hand by inserting levers in the openings 54 and turning the disc.

In making a cage, the longitudinal rods 16 are placed in the slots 21 in the face plate 17 and on the dogs 40 of the supports 35. The engaging hooks 49 are then dropped into place so that they engage the outer surfaces of the rods and hold them against the V-shaped surfaces of the dogs. The springs 51 cause the hooks to engage the rods until manually released. When the hooks are moved outwardly by means of the handles 52, the springs 51 are then displaced sufficiently so that the rods may be removed.

Iron wire is wound around the rods 16 beginning at the head stock 3, by operating motor 2. The last few turns are wound by turning the mandrel and cage by hand, as has been previously explained. When the iron wire has been wound on the rods, it is fastened to them by means of smaller iron wire 58. Any suitable means may be employed in fastening the wire on the longitudinal rods 16, but we prefer to use a bag tie tool, well known in the art.

When a reinforcing cage has been completed, the tail stock is loosened, disengaged from the mandrel and thrown back out of the way.

The holding hooks 49 are then disengaged, as has been hereinbefore described, and the lever arm 32 is driven by means of a suitable lever to the right so that the cam surfaces 33 of the lever arm are caused to force the slid- 95 able face plate 22 into substantial engagement with the fixed face plate 17, thus causing the stripper pins 23 to drive the reinforcing rods 16 out of engagement with the fixed face plate. The longitudinal motion of the reinforcing rods causes the dogs 40 on the supports 35 to be turned about their pivots 36 100 thus disengaging the reinforcing rods.

Our device provides improved means for manufacturing reinforcing cages. The cages may be readily and quickly made and the 110 entire process consumes less time and thus provides a structure which is inexpensive in cost.

Although we have described a specific modification of our device, other modifications 115 may be made by those skilled in the art. For instance, the slidable collar of the supports 35 may be dispensed with. Other means may be used to disengage the rods from the fixed face plate 17. These and other modifications 120 may be made without departing from the spirit and scope of our invention as defined in the appended claims.

We claim as our invention:

1. In a cage-making machine, a lathe bed, 125 a mandrel carried by the lathe bed, a driving motor and reduction gearing mounted on the lathe bed for driving the mandrel, a face plate mounted on the mandrel for supporting one end of the rods of said cage, a plurality 130

of supports spaced along said mandrel, and a disc for supporting the other end of the reinforcing rods, said disc being adapted to be manually rotated.

5. 2. In a cage-making machine, means for holding the reinforcing rods of the cage in place comprising a disc, dogs radially disposed on said disc, and hooks for holding said rods in engagement with said discs.

10. 3. In a cage-making machine, a mandrel, means for holding the cage in place on the mandrel comprising a fixed face plate and a plurality of supporting members, and means for driving said cage longitudinally out of engagement with said holding means, said driving means comprising a slidable face plate, stripper pins attached to said slidable face plate, and means for sliding said slidable face plate towards said fixed face plate to engage said stripper pins with said cage.

15. 4. In a cage-making machine, a support for reinforcing rods comprising a mandrel, a supporting member mounted on said mandrel, dogs movably fastened to said supporting member and adapted to support said reinforcing rods when the dogs are in engaged position against the said supporting member, and means for holding said dogs in engaged position.

20. 5. In a cage-making machine, a support for reinforcing rods comprising a mandrel, a supporting member mounted on said mandrel, dogs movably fastened to said supporting member and adapted to support said reinforcing rods when the dogs are in engaged position against the said supporting member, and means for holding said dogs in engaged position, said holding means comprising a slidable collar adapted to engage said dogs.

25. 6. In a cage-making machine, a support for reinforcing rods comprising a mandrel, a supporting member mounted on said mandrel, dogs movably fastened to said supporting member and adapted to support said reinforcing rods when the dogs are in engaged position against the said supporting member, means for holding said dogs in engaged position and holding means for engaging said rods with said dogs.

30. 7. In a cage-making machine, means for disengaging a finished cage comprising a mandrel, a fixed face plate having a collar portion mounted on said mandrel and provided with slots about its periphery for supporting the reinforcing rods of said cage, a slidable face plate provided with stripper pins adapted to disengage said rods from said fixed face plate when said slidable face plate is engaged and means for engaging said sliding plate comprising a cam and lever.

35. 8. In a cage-making machine, means for disengaging a finished cage comprising a mandrel, a fixed face plate having a collar portion mounted on said mandrel and provid-

ed with slots about its periphery for supporting the reinforcing rods of said cage, a slidable face plate provided with stripper pins adapted to disengage said rods from said fixed face plate when said slidable face plate is engaged with said fixed plate and means for engaging said sliding plate comprising a cam and lever.

40. In testimony whereof, we have hereunto subscribed our names this 20th day of August, 1927.

EMIL E. HAWKINSON.
NED W. BURBRIDGE.
